UNITED STATES PATENT OFFICE

2,420,426

COMPRESSOR

Herbert W. Harrer, New Washington, Ohio

Application April 30, 1945, Serial No. 590,980

7 Claims. (Cl. 230—56)

1

The device forming the subject matter of this application is a compressor for fluids, preferably air.

One object of the invention is to provide a compressor having oppositely disposed power cylinders, the pistons whereof are connected in a novel way to the pistons of first stage compression cylinders and to the pistons of second stage compression cylinders.

Another object of the invention is to provide a novel means whereby the exhaust from the internal combustion or power cylinders may be made effective to heat air which is delivered into the said cylinders.

A further object of the invention is to supply a novel means whereby air which is compressed on the back stroke of the first stage cylinders will be made effective to scavenge the products of combustion from the power cylinders.

Another object of the invention is to supply a novel impact wheel which is actuated by the escaping exhaust from the power cylinders, to carry certain parts of the machine over dead centers.

Other and further objects of the invention will be made manifest as the description proceeds.

A mechanic who abides by what is claimed may make changes in the precise structure shown, without departing from the spirit of the invention.

In the drawings:

Figure 1 shows in top plan, a compressor constructed in accordance with the invention;

Figure 2 is a side elevation;

Figure 3 is a vertical longitudinal section showing approximately one-half of the compressor;

Figure 4 is a vertical longitudinal section showing the cooperating half of the compressor;

Figure 5 is a horizontal section taken through the casing approximately on the line 5—5 of Figure 3, the cylinders directly thereunder being shown in section;

Figure 6 is a vertical transverse section taken approximately on the line 6—6 of Figure 3;

Figure 7 is a vertical transverse section taken approximately on the line 7—7 of Figure 4;

Figure 8 is a horizontal sectional view showing certain of the cylinders and attendant parts;

Figure 9 is a section on the line 9—9 of Figure 5, parts being omitted.

In carrying out the invention, there is provided a casing or support C, including an intermediate member embodying a shell 1, having end walls 2. The casing C comprises tapered end members 3 assembled with opposite ends of the shell 1. There is a transverse partition 4 in each end member 3, and each end wall 2 likewise forms a partition. The casing C has detachable access plates 5, located as preferred.

Power cylinders 6 are secured to the end walls 60

2

2 and project into the intermediate member 1—2 of the casing, the cylinders being open at their inner ends. The cylinders 6 are supplied with transverse exhaust ports 7 and with transverse scavenging ports 8. The scavenging ports 8 are located nearer to the open ends of the cylinders 6 than are the exhaust ports 7.

Power pistons 9 are mounted for reciprocation in the power cylinders 6 and are carried by rods 10, secured to a first cross head 100.

First stage compression cylinders 11 are provided and are disposed in parallel relation, these cylinders extending between the partitions 2 and 4. Pistons 12 are mounted for reciprocation in the cylinders 11 and are carried by rods 14, which are secured to the cross head 100. Air is admitted to the spaces between the partitions 2 and 4 in any suitable way, for instance, through ports P in the end members 3. Air is admitted to the cylinders 11, ahead of the pistons 12, through outwardly closing check valves 15 (Figs. 3 and 8) carried by the cylinders, and located adjacent to the partitions 4. For a purpose to be described hereinafter, air is admitted behind the pistons 12 through similar check valves 16, located in the cylinders, and shown in Fig. 8.

Second stage compression cylinders 17 are secured to the partitions 4, within the casing parts 3, in axial alignment with the power cylinders 6.

30 The heads of the first stage cylinders 11, the partitions 4, and the heads of the second stage cylinders 17 have ducts 18, by which air can pass from the first stage cylinders to the second stage cylinders, check valves 19 being located in the ducts and closing toward the first stage cylinders. The second stage cylinders 17 are provided with outwardly opening check valve mechanisms 20 (Fig. 3) located near the partitions 4. From the check valve mechanisms 20, conduits 21 lead to a storage tank or the like (not shown).

In their outer ends, the cylinders 17 are vented as shown at 22, to facilitate reciprocation of pistons 23 in the cylinders, the pistons being carried by rods 24, secured to the intermediate portions of second cross heads 25. Rods 26 external to the cylinders 17 and 6, are secured terminally to the cross heads 25 and 100, and reciprocate in the partitions 2 and 4, and in flanges 27 on the cylinders 17, 11 and 6.

50 Oil, water or some other liquid is maintained at a predetermined level in the intermediate member of the casing C. The lowermost of the rods 26 (Figure 3) carries agitators 28, which operate on the liquid in the casing flinging it about, as said rods 26 reciprocate, a cooling and lubrication of the working parts thus being effected. If water is used for cooling, lubrication of the cylinders will have to be done by a system of mechanical lubricators not shown.

55 Housings 29 are fixed in the intermediate mem-

ber 1—2 of the casing C. Exhaust headers 30 (Figures 3 and 9) are in communication with the exhaust ports 7 of the power cylinders 6, and communicate with the housings 29. The housings 29 communicate, as shown at 31 in Figures 1 and 3, with receivers 32 mounted on the intermediate portion of the casing C, and having exhaust outlets 33. Within receiver 32 is located an air tank 34.

Shafts 35 (Figures 3 and 4) are journaled in the intermediate portion of the casing C and carry, within the housings 29, impact wheels 36, responsive to the exhaust passing through the housings. The impact wheels 36 comprise a small number of grouped blades 37. The blades may be altered in number but, in any event, they extend through a limited arc only, leaving a solid portion which is adapted to cover the exhaust ports, during the period of rotation.

Eccentrics 38 and 39 are secured to the shafts 35, externally of the housings 29. The eccentrics 38 and 39 carry wrist pins 40 whereunto are pivoted pitmans 41, pivotally mounted on pins 42 mounted in the cross head 100.

The eccentrics 39 cooperate with the plungers 43 of fuel pumps 44, mounted on the walls 2 of the casing C. The sources of fuel supply for the pumps 44 are marked by the numeral 45. Conduits 46 lead from the pumps 44 to the power cylinders 6. By adjusting the length of the fuel pump stroke, the amount of fuel delivered is determined and metered.

The eccentrics 38 cooperate with the plungers 47 of air starting valves 48, mounted on the partitions 2. The tanks 34 are adapted to contain air under pressure, which is heated by the exhaust which passes through the receivers 32. Conduits 49 lead from the tanks 34 to the air starting valves 48, and in the conduits 49 are interposed cut-off valves 50, under the control of an operator. Conduits 51 lead from the air starting valves 48 to the power cylinders 6. The starting air works on the power piston that is expanding and at full stroke is shut off and then automatically changed to the other power pistons. This is timed and actuated by the eccentrics 38 and air starting valves 48. When motion of the unit has been attained by its own power the valve 50 is secured. During this starting and warming up period, the compression cylinders 11 and 17 are vented to cause easier motion.

Air cylinders 52, shown in Figures 9 and 3, are secured to the power cylinders 6 and are disposed transversely thereof, the scavenging ports 8 of the cylinders 6 being in communication with the air cylinders 52 shown in Figures 8 and 9. The cylinders 52 extend through the shell 1 of the casing C, and include heads 53, wherein breather ports 54 are formed, the breather ports being in communication with the atmosphere external to the casing C. Pistons 55 are slidably mounted in the air cylinders 52 and are advanced by compression springs 56, interposed between pistons 55 and heads 53.

Transverse manifolds 57 (Figure 8) are mounted in the first stage compression cylinders 11, in close relation to the end walls 2 of the shell 1, the manifolds being open at their ends. The manifolds 57 have a branch 59 in communication with the cylinders 52. A check valve 61 is interposed in each branch 59, the check valve opening toward the cylinders 52.

The pitmans 41 constitute means for imparting rotation to the eccentrics 38 and 39. The air starting valves 48 are operated by the eccentrics

38 on the shafts 35, since the plungers 47 of air starting valves 48 engage the eccentrics. The air in the tanks 34 is heated and expanded, since the exhaust produced when the power pistons are actuated by internal combustion, enters the receivers 32 by way of the connections 31 and leaves by way of the outlets 33. This air which is pre-heated, is more powerful than air of room temperature, and is discharged into the main supply tank for use. The air comes in the tank only to be expanded by the exhaust heat, giving it more power just before using.

The plungers 43 of the metering fuel pumps 44 cooperate with the eccentrics 39 on the shafts 35. The pumps 44 are put into operation, the pumps receiving fuel from the conduits 45, and passing the fuel by way of the conduits 46 to the power cylinders 6, through an injection valve into the highly compressed air in the cylinders, causing immediate combustion and expansion on the Diesel principle which is automatic due to high cylinder pressure and the heat of the compressed air. However, an ignition system can be used.

The pistons 12 of Figs. 3 and 9, moving to the right, draw in air through the check valves 15, the air being supplied through the ports P or their equivalent. When the pistons 12 of Fig. 3 move to the left, under the influence of the pistons 9 of Figs. 3 and 4, air is forced past the check valves 19 into the cylinders 17. When the piston 23 of Fig. 3 moves to the right, along with the cross head 100, air is forced outwardly past the check valve 20 and through the outlet 21 to the place of storage for use.

Operation

Referring to Figure 3, the reciprocating cross head 100 imparts rotation to the eccentrics 38 and 39 by way of the pitmans 41, and to the shafts 35. The shafts 35 rotate impact wheels 36.

As the piston 9 moves to the right in Figure 3, to make a power stroke, the piston uncovers the exhaust ports 7. The exhaust passes through the headers 30 and enters the housings 29. From the housings 29, the exhaust products pass through the connections 31 into the receivers 33, to heat the air tanks 34, the exhaust finding an exit through the outlets 33. With this movement of the piston 9 shown in Figure 3, the piston 9 at the opposite side of the cross heads 100, moves in its cylinder to cover the exhaust ports 7 of its cylinder, and move to compress a charge in its cylinder.

Referring to Figure 5, it will be seen that the impact wheels 36 do not have a full set of blades 37, circumferentially considered. The centers of mass of the impact wheels 36 do not coincide with the axes of rotation of the shafts 35. Consequently, the impact wheels 36 act as an eccentric weight which aids in carrying the crank pins 40 over dead centers. These impact wheels act to direct the exhaust gases into the receivers 32 heating the air in the tanks 34 for distribution into the power cylinders.

Passing to Figure 8, when the pistons 12 make a compression stroke, air is drawn into the cylinders 11 through the check valves 16. When the pistons 12 make a return stroke, air in the cylinders 11 is forced through the manifolds 57 and the branch 59, past the check valve 61, into the cylinders 52. At that time, the pistons 9 have closed the scavenging ports 8, and the pistons 55 are forced to retire, under air pressure, compressing the springs 56. As the piston 9 moves to the right in Figure 3, it uncovers the ports 8 in the

cylinder 6, and the spring 56 advances the piston 55, air in the cylinder 52 is forced through the ports 8 into the cylinder 6, to clear it of burned gases, and the product leaves by way of the exhaust ports 7, leaving the cylinder 6 full of clean cool air.

The operation has been dealt with hereinbefore step by step, but by way of summary, the power pistons 9 of Figures 3 and 4 actuate the stage-compression pistons 12 and 23, and compressed air leaves the cylinders 17 by way of the outlet conduits 21. The cylinders 6 are scavenged by the mechanism shown in Figures 8 and 9. The eccentrics 38 and 39 cooperate, respectively, with the valves and pumps 48 and 44, and the valves and pumps, respectively, supply the cylinders 6 with air and with combustive fuel.

The manifolds 57, the branch 59, and the cylinders 52 constitute a conducting means leading from the spaces behind the compression pistons 12 to the scavenging ports 8.

What is claimed is:

1. In a compressor, an internal combustion power cylinder having a scavenging port, a power piston slideable in the power cylinder, a compression cylinder, a compression piston slideable in the compression cylinder, the compression cylinder having a check valve inlet and a check valve outlet located ahead of the compression piston, and having a check valve inlet disposed behind the compression piston, means for connecting the pistons for movement together, and a third cylinder communicating with the scavenging port, a conduit connection between the third cylinder and the space behind the compression piston, a check valve interposed in the conduit, a piston slideable in the third cylinder and retiring under pressure derived from the conduit connection, and yieldable means for advancing the last specified piston after it has retired, the power piston constituting a closure for the scavenging port during the retirement of the last specified piston.

2. In a compressor, a power cylinder having an exhaust port, a power piston slideable in the power cylinder, a compression cylinder, a compression piston slideable in the compression cylinder, means for connecting the pistons for movement together, said means including a cross head, a housing having an exhaust outlet, means for conducting exhaust from the exhaust port to the housing, an exhaust-actuated impact wheel supported for rotation in the housing, a valve, a conduit leading from the valve to the power cylinder, means for actuating the valve, said means comprising a rotary member connected to the impact wheel, and an operative connection between the cross head and the rotary member and including a wrist pin on the rotary member, the impact wheel comprising a segmental group of rotating blades, arranged throughout only a portion of the radius of the wheel, overbalancing the wheel, whereby the wheel is rotated, passing the wrist pin over dead centers.

3. A compressor constructed as set forth in claim 2, and wherein the valve is an air starting valve, and means for supplying air thereto for starting or setting the unit in motion by the pressure of the air from the starting tank through connections to said tank.

4. A compressor constructed as set forth in claim 2, and wherein the valve is a metering fuel pump, and means for supplying fuel thereto.

5. In a compressor, a power cylinder having an exhaust port, a power piston slideable in the power cylinder, a compression cylinder, a compression

piston slideable in the compression cylinder, means for connecting the pistons for movement together, said means including a cross head, a housing having an exhaust outlet, means for conducting exhaust from the exhaust port to the housing, an air starting valve, a conduit leading from the air starting valve to the power cylinder, means for supplying air to the air starting valve, a fuel pump, a conduit leading from the fuel pump to

10 the power cylinder, means for supplying fuel to the fuel pump, an impact wheel in the housing and actuated by exhaust moving through the housing, eccentrics connected to the impact wheel to rotate therewith and constituting actuators for the pump, and valve and an operative connection between the cross head and the eccentrics, said connection including a wrist pin on one of the eccentrics, the impact wheel comprising a segmental group of blades constituting means for passing the wrist pin over dead centers.

15 6. In a compressor, a support, an internal combustion power cylinder carried by the support and having an exhaust port, a power piston slideable in the power cylinder, a compression cylinder carried by the support, a compression piston slideable in the compression cylinder, a connection between the pistons, a receiver having an outlet, means for conducting exhaust from the exhaust port to the receiver, an air tank in the receiver, 20 means for conducting heated air from the tank to the power cylinder operating the piston therein, and means for supplying the power cylinder with fuel.

25 7. A compressor comprising oppositely disposed power cylinders, a first cross head located between the power cylinders, power pistons slideable in the power cylinders and connected to the first cross head, second stage compression cylinders located in a common longitudinal axis with the power cylinders and having outlets, second stage pistons slideable in the second stage cylinders, second cross heads located at the outer ends of the second stage cylinders and connected to the second stage pistons, connections between the first 30 and second cross heads, a pair of first stage compression cylinders located between each power cylinder and the corresponding second stage cylinder and located at opposite sides of said axis, first stage pistons slideable in the first stage cylinders and connected to the first cross head, means for admitting fluid to the first stage cylinders, and check valve connections between each of the first stage cylinders and the corresponding second stage cylinder.
